(57) **CLAIM**

The ornamental design for an internal combustion engine, as shown.

DESCRIPTION

FIG. 1 is a front perspective view of a portion of an internal combustion engine showing my new design;

FIG. 2 is a front elevational view thereof;

FIG. 3 is a right side elevational view thereof;

FIG. 4 is a left side elevational view thereof; and

FIG. 5 is a top view thereof.

The broken line showing of environmental structure is for illustrative purposes only and forms no part of the claimed design.
